EXPANSIBLE VEHICLE

Carl W. Sundberg, Bloomfield Hills, Mich., assignor to
American Metal Products Company, Detroit, Mich., a
corporation of Michigan

Filed Apr. 13, 1962, Ser. No. 69,702

Term of patent 14 years

(Cl. D14—3)

FIGURE 1 is a perspective view of an expansible vehicle showing my new design;

FIGURE 2 is a side elevational view thereof showing the vehicle in an expanded condition with the panels and supports in open position and the wheels retracted; and

FIGURE 3 is a rear elevational view thereof showing the vehicle in an expanded condition.

The side of the vehicle not shown in the drawings is substantially the same as the corresponding side which is shown. The dominant features of my design reside in the portions shown in full lines.

I claim:

The ornamental design for an expansible vehicle, substantially as shown and described.
